POWER HANDLE FOR A BARBECUE SPIT OR THE LIKE

Jean Otis Reinecke, Oak Park, and John Mercer Sherrer,
Barrington, Ill., assignors to Blairco Industries, Inc.,
Olney, Ill., a corporation of Delaware

Application June 17, 1957, Serial No. 46,622

Term of patent 14 years

(Cl. D81—10)

Figures 3 and 4 are end elevational views taken from the left and right, respectively, of Figure 1.

We claim:

The ornamental design for a power handle for a barbecue spit or the like, substantially as shown.
